SOLE-CONDITIONING MACHINE

Harold E. Marasco, Swampscott, Mass.

Application January 31, 1951, Serial No. 208,808

9 Claims. (Cl. 12—1)

1

This invention relates to machinery useful in the manufacture of shoes and in particular to machines for treating outsoles to impart to them characteristics desirable in the operation of cement sole attaching.

Before an outsole can readily be attached to the shoe bottom its coating of cement must be activated or otherwise rendered tacky and adhesive. Also the leather must be humidified or mulled to impart flexibility and plasticity sufficient to enable the sole to follow and retain the rather severe contours of the shoe bottom.

While many machines and systems have been employed with varying success to condition outsoles preparatory to cement sole attaching or to condition cemented insoles for cement lasting, no prior machine to my knowledge has successfully combined the activation of the cement and the mulling of the leather.

The most important object of my invention is to improve the economy and facility with which soles may be conditioned preparatory to attachment to the shoe bottom.

Another object of my invention is to combine in one machine the functions of mulling and cement activating, thereby decreasing the number of machines and operations heretofore required.

An important feature of the invention resides in the combination of a pair of cooperating rolls, one of which is perforated or foraminous and supplied interiorly with wet steam from a suitable steam generator and wherein both rolls are heated, the arrangement being such that a sole may be fed between the rolls with its cement-coated surface against the foraminous roll and the grain surface against the other heated roll. In the operation of the machine the sole is simultaneously heated, moistened, and flexed under pressure.

An important advantage flowing from the employment of a machine constructed in accordance with this invention is that soles coated with thermoplastic cement are readily processed, since the surfaces of the rolls may be heated sufficiently to cause the cement to become plastic, a result difficult and impractical to produce by the application of hot water vapor alone. When soles are subjected to a hot saturated atmosphere long enough to activate thermoplastic cement, it is found that the sole must be left in the press for an excessive time in order to produce a satisfactory bond with the shoe bottom.

These and other objects and features of my invention, together with incident advantages,

2

will more readily be understood and appreciated from the following detailed description of a preferred embodiment thereof selected for purposes of illustration and shown in the accompanying drawings, in which:

Fig. 1 is a view in side elevation of a machine constructed in accordance with the invention,

Fig. 2 is a view in cross section along the line 2—2 of Fig. 3,

Fig. 3 is a view in rear elevation with portions being removed and others shown in section, and

Fig. 4 is a plan view of the machine.

In the embodiment of the invention shown in the drawings the machine is organized about a

frame composed essentially of a flat metal base 10 and integral side walls or standards 12 and 14. Near the base 10, the front of the frame is closed by a wall or plate 16 extending about a third of the way up from the base 10. In the

rear a wall 18 closes the frame and extends up from the base 10 about one half the height of the machine. These walls define an enclosure or reservoir employed as a steam generating

chamber covered at its top by an integral wall 20 sloping downwardly from side to side. A drain plug 22 is let into the wall 14 just above the cover 20 in order to permit the removal of water dropping on the plate from above and collecting above the low point.

The reservoir beneath the cover 20 is provided with a drain 24 disposed in the front wall 16 and with a fill pipe 32 which may be conveniently led to any suitable water supply (not shown) such as a constant-level barometric feeder of ordinary construction.

An immersion heater 26 projects into the reservoir through the side wall 12 and terminates exteriorly in an electrical plug 27. The reservoir is also provided with a thermostat 28 also projecting through the wall 12. Finally a plug 30 is

let into the wall 18 to provide accommodation for a thermometer, if desired. Ordinarily the operation of the heater will be controlled by the thermostat 28 suitably connected in conventional fashion to monitor the supply of current to the heater 26.

Disposed in the frame above the reservoir is a perforated roll comprising a cylindrical foraminous shell 34 of brass or other suitable material mounted at each end on a hub 36 keyed in turn to a hollow foraminous shaft 40 journaled in heat-resistant bearings 42 mounted in the side walls 12 and 14 and terminating adjacent the wall 14 in a solid shaft 54. The other end 55 of the shaft 40 opens into a hollow block 44

provided into a curved chamber or conduit 46 communicating with the reservoir through a hole 48 in the wall 12.

The surface of the shell 34 is provided with a continuous spiral groove 50 the bottom of which is interrupted by a multiplicity of small through-and-through perforations 52 leading to the space between the shaft 49 and the shell 34.

Mounted above the roll 34 is a second hollow roll comprising a cylindrical shell 58 also of brass and mounted at each end upon the hub 60 keyed to a solid shaft 62. At one end the shaft 62 turns in a bearing block 64 working in a slot in the side wall 14. Adjacent and exterior of the block 64 the shaft 62 is provided with a gear 66 which meshes with a similar gear 56 secured to the shaft 54.

A helical compression spring 68 bears at its lower end against the bottom of a socket in the top of the block 64 and at its other end against a plunger 72. A bolt 70 is threaded into the top of the plunger 72 and also through a cap plate 74 secured to the tops of the walls 12 and 14 by four screws 76.

The side wall 12 is provided with a slot 78 in which slides a bearing block 80 in which the other end of the shaft 62 is journaled. The top of the block 80 is provided with a cylindrical socket 94 in which is seated the lower end of a helical compression spring 92 engaged at its upper end by a plunger 90. A bolt 86 is threaded through the plate 74 and into the plunger 90, being held in adjusted position by means of a lock nut 88. It will now be evident that the roll 58 may yield upwardly away from the roll 34 in response to pressure from beneath. The tension of the springs 68 and 92 may be adjusted by manipulation of the bolts 70 and 86 to urge the rolls together under desired spring pressure.

In the bottom of the bearing block 80 there is provided a stop bolt 82 provided with a lock nut 84. By manipulation of the bolt 82 the block 80 together with the roll 58 may be rocked up and down. By means of that adjustment the two rolls 34 and 58 may be brought into exact parallelism when the machine is installed.

In order to apply heat to the surface of the upper roll 58 I employ a shoe or curved block 100 which embraces an arc of the periphery of the roll 58 and is held in position by a pair of guide pins 104 mounted in the plate 74 and working in holes bored in the block. The block 100 is also bored to provide a pair of sockets 108 receiving helical compression springs 104 received at their upper ends in shallow sockets in the lower surface of the plate 74 and serving to urge the shoe 100 against the roll 58.

A pair of electrical resistance heaters 106 are disposed in bores running longitudinally through the shoe 100 and serve to heat the block to a desired temperature.

As shown in Fig. 2, the lower roll 34 is similarly heated by a shoe 110 bored as shown at 116 to receive a pair of electric heating units 118 (Fig. 1). The block 110 is held in position by a pair of guide pins 114 and urged against the roll 34 by means of a pair of springs 112 working in sockets in the outer face of the block 110 and in shallow sockets in the inner face of a plate or strap 116 secured at each end to one of the side walls 12 and 14. The heaters 118 may be thermostatically controlled by conventional means (not shown) to maintain a predetermined roll surface temperature.

To remove excess moisture from the rolls 34

and 58, I provide them with wipers. At the rear of the machine a wiper bracket 120 is mounted on pivot pins 122 threaded in the side walls 12 and 14 and urged toward the surface 5 of the roll 34 by a spring 126 working against the wiper bracket 120 and the rear wall 18. A long felt strip 124 is pressed into a slot on the inner face of the wiper bracket 120 and wipes the surface of the rotating roll 34.

A similar wiper fixture serves the rear of the roll 58, including a wiper bar or bracket 128 mounted on pivot pins 130 and urged upon the roll 58 by means of a pair of springs 132 embracing screws 134 threaded in a cross member 136. The bracket 128 carries a long strip 126 of felt or other absorbent material. In the front of the machine the roll 58 is served by a wiper including a felt strip 138 held in a transverse bar 140 mounted to swing on pivot pins 142 and urged against the roll 58 by a pair of springs 144 embracing bolts 146 threaded through a cross member 148 spanning the side walls 12 and 14.

Inasmuch as cement particles may lodge on the 25 surface of the roll 34, I provide a scraper blade 152 secured to a transverse bracket 150 by a pair of screws 154. The ends of the bracket 150 are turned up to form upstanding lips 156 at each end of the scraper. The bracket 150 is mounted 30 at each end on pivot pins 157 threaded through the side walls 12 and 14, and set screws 158 are threaded through the bracket 150 in position to engage the top of the rear wall 18 and to provide means for exerting positive pressure by the 35 scraper 152 upon the surface of the roll 34.

A plate or table 162 is secured to the top of the front cross member 113 on a level with the height of the rolls 34 and 58, and a pair of angle iron side guide plates 164 are secured to the upper 40 surface of the table 162 by a pair of screws 168 working in slots 166 cut in the plates 164. The guides 164 may be set at a width convenient to guide and direct a sole lengthwise into engagement with the rolls 34 and 58.

In operating the machine a sole carrying a 45 coating of cement is placed on the table 162 and pushed by hand into engagement with the rolls which then feed the sole through to the rear of the machine. The cement-coated side of the sole 50 is placed face down so that it encounters the heated surface of the roll 34 and is also subjected to wet steam emanating from the interior of the roll 34 through the holes 52. The sole is also heated on its uncoated side by contact with the 55 hot surface of the upper roll 58. Excess moisture accumulating on the rolls is removed by the wipers 124, 126, and 138. In its passage through the rolls the sole is also flexed somewhat by the pressure exerted upon it, although the roll 58 will yield upwardly in its spring-loaded bearings, to accommodate soles of different thickness or soles of uneven thickness.

The activation of sole cements, such as neoprene type cement or Buna N type cement is primarily accomplished by the heat of the roll 34 assisted by the wet steam. The tacky point of the cement will determine the desirable operating temperature for the rolls. I have found about 145° C. to be satisfactory for Buna N type cement. Furthermore the combination of heat, moisture, pressure and flexing not only activates the sole cement but also renders the sole plastic as a whole, by which is meant that it becomes sufficiently pliable and workable to adapt itself quickly to the contours of the shoe bottom and then,

as is characteristic of leather, retain those contours after removal from the sole-attaching press. The fact that the sole is properly conditioned as to moldability and activation results in materially reducing the time during which the sole is in the press, since a good bond is obtained in minimum time. Consequently the production rate of a multi-station press may be increased, or the number of presses reduced without lowering daily production. Moreover it is unnecessary to employ a sole molding machine as a means of conditioning the sole for attaching, since the pressure of the press is sufficient to mold a sole conditioned on a machine embodying my invention.

There are additional advantages incident to the operation of the machine of my invention. For example, the volume of water required is rather small because water vapor condensed at the contact surface will fall on the roll and immediately be re-vaporized. The stream passing through the holes in the heated roll will be further heated and thereby soften and loosen the fibers on the cemented surface of the sole and cause maximum penetration of the cement. The grooves in the lower roll distribute the water vapor over a larger area of the sole than would be the case with a smooth foraminous roll. Finally, the machine is readily constructed as a small bench machine with simple controls of conventional nature.

Having thus disclosed my invention what I claim as new and desire to secure by Letters Patent is:

1. A machine for conditioning soles, comprising a frame, a hollow perforated roll mounted for rotation in said frame, a reservoir disposed in said frame, means for heating and vaporizing liquid contained in said reservoir, a conduit connecting said reservoir to the interior of the perforated roll, a presser roll disposed for rotation in said frame parallel and adjacent the perforated roll, and means for heating the surface of said presser roll.

2. A machine for conditioning soles, comprising a frame, a hollow perforated roll mounted for rotation in said frame, a reservoir disposed in said frame, means for heating and vaporizing liquid contained in said reservoir, a conduit connecting said reservoir to the interior of the perforated roll, a presser roll, spring loaded bearings disposed in said frame and journaling said presser roll parallel to and adjacent said hollow perforated roll with provision for yielding movement, and means for heating the surface of the latter roll.

3. A machine for conditioning soles, comprising a frame, a hollow roll mounted in the frame and having spiral surface grooves and perforations lying within said grooves, a reservoir, means for heating and vaporizing a liquid contained in said reservoir, a conduit connecting

said reservoir to the interior of said hollow roll, a second roll mounted in said frame adjacent and parallel to said hollow roll, and means for heating the surfaces of both rolls.

4. A machine for conditioning soles, comprising a frame, a hollow perforated roll journaled in the frame, a reservoir disposed in said frame, means for heating and vaporizing a liquid contained in said reservoir, a second roll mounted for rotation in said frame adjacent and parallel to said hollow roll, means for conducting vapors from said reservoir to said hollow roll, a block having an arcuate surface engaging said second roll, and means for heating said block.

5. A machine for conditioning soles, comprising a frame, a hollow perforated roll journaled in the frame, a reservoir disposed in said frame, means for heating and vaporizing a liquid contained in said reservoir, a second roll mounted for rotation in said frame adjacent and parallel to said hollow roll, means for conducting vapors from said reservoir to said hollow roll, a block disposed adjacent each roll and having an arcuate roll-engaging surface, and heating elements mounted in said blocks.

6. A machine for conditioning soles, comprising a frame, a hollow foraminous roll mounted for rotation in said frame, means associated with said frame for generating vapor and conducting vapor to the interior of the roll, a second hollow roll, bearings mounting said second roll adjacent and parallel to the first roll with provision for limited yielding movement, moisture absorbent wipers bearing on said rolls and mounted in said frame, and means for heating the outer surface of both rolls.

7. A sole conditioning machine comprising a pair of cooperating rolls one of which is hollow and foraminous, means for supplying heated water vapor to the interior of the hollow foraminous roll, arcuate shoes bearing on both of said rolls, means for heating said shoes, and means for rotatably mounting the rolls.

8. A sole conditioning machine comprising a pair of cooperating rolls one of which is hollow and foraminous, wipers mounted in position to bear on said rolls, means for supplying heated water vapor to the interior of the hollow foraminous roll, arcuate shoes bearing on both of said rolls, means for heating said shoes, and means for rotatably mounting the rolls.

9. A sole conditioning machine comprising a pair of cooperating rolls one of which is hollow and foraminous and provided with surface grooves, means for supplying heated water vapor to the interior of the hollow foraminous roll, arcuate shoes bearing on both of said rolls, means for heating said shoes, and means for rotatably mounting the rolls.

HAROLD E. MARASCO.
